UNITED STATES PATENT OFFICE.

ELMER L. KNOEDLER, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

PACKING-BOX FOR MANTLES, &c.

1,145,491.

Specification of Letters Patent.

Patented July 6, 1915.

Application filed February 12, 1913. Serial No. 747,937.

To all whom it may concern:

Be it known that I, ELMER L. KNOEDLER, a citizen of the United States, and resident of Gloucester City, Camden county, New Jersey, have invented a new and useful Improvement in Packing-Boxes for Mantles, &c., of which the following is a full, clear, and exact description, reference being had to the accompanying drawings, forming part of 10 this specification, in which—

Figure 1 is a longitudinal section of a packing box embodying my invention, and showing the gas mantle supported therein; Fig. 2 is a plan view of the box with the 15 cover removed; and Fig. 3 is a perspective view of the ring removed.

My invention has relation to packing boxes, more especially designed for packing inverted incandescent mantles, but which 20 can also be used for other articles.

The object of my invention is to provide a box of this character which can be easily and cheaply made, which will permit the mantle to be quickly and readily packed and 25 unpacked without danger or injury thereto, and which will obviate the use of glue or other fastenings for securing the supporting ring in the tube or casing of the box.

Another object is to provide a ring of 30 this character, which will prevent the crushing in of the upper portion of the box and will reinforce the box at that portion in which the legs of the mantle-supporting ring are located, to prevent the legs and 35 ring from being broken.

A further object is to provide a supporting ring which will exert a shaping or reshaping action upon the tube or casing when 40 it is inserted therein.

The precise nature of my invention will be best understood by reference to the accompanying drawings, which will now be described, it being premised, however, that 45 changes may be made without departing from the spirit and scope of my invention as defined in the appended claims.

Referring to the accompanying drawings, in which I have shown the preferred embodiment of my invention, the numeral 2 designates the tubular body of the box, which may be of any suitable material, preferably paper or pasteboard, and which is provided with the usual bottom 3 and removable cover 4. 5 designates the supporting ring having a horizontal body por-

tion, an upwardly extending outer flange 6, and a downwardly and outwardly extending inner flange 7. This ring is made of any suitable material, preferably metal, formed by drawing and stamping in such a manner 60 that the junction between the flanges and the body portion is slightly rounded.

The ring is forced into the upper end of the box, so that the upper edge of the flange 6 is on a line with the top of the box, the 65 height of this flange being about equal to the height of the legs of the mantle-supporting ring 8. The size of the ring is such that it will be held in position within the box by frictional engagement therewith, but, if 70 desired, it may be secured therein by slightly crimping the flange 6, or by the use of glue or paste, or any other suitable device.

The flange 7 of the ring is flared outwardly toward the body of the box, and the 75 junction between said flange and the body of the ring is rounded as shown in Fig. 1. The flaring outwardly of this flange will avoid all danger of injury to the mantle by contacting with the lower edge of the flange, 80 while the rounded junction between the flange and the body will also prevent injury to the mantle when the mantle is withdrawn from the box.

The ring is preferably of greater rigidity 85 than the material of which the tubular bodies 2 are usually composed, so that when they are inserted within such bodies they exert a shaping or reshaping action thereon, bringing the bodies back to approximately 90 true cylindrical form. These tubular bodies are very apt to become misshapen or deformed in handling or from unequal drying

after being labeled, and heretofore it has been necessary to throw away large numbers of such boxes, owing to this fact. By reason of the reshaping action of the ring herein described, many of the boxes heretofore thrown away can be redeemed and 95 utilized. The holding of the tubular members to their true cylindrical form insures the proper centering of the supported mantle therein, and prevents contact between the mantle and the walls of the body, especially when inserting and removing the mantle from the box. The upwardly extending flange will avoid all danger of crushing in the upper portion of the box at 100 that portion in which the legs of the mantle-supporting ring are seated, which will

105

110

overcome all danger of injury to the legs of the mantle-supporting ring.

I claim:

1. A packing box for mantles, comprising a tubular casing of pasteboard or similar non-rigid material, and a previously shaped metal ring for supporting the mantles secured within one end portion of the casing and exerting a shaping action thereon to form and preserve its desired shape, said metallic ring having a supporting ledge or flange with a rolled-over inner edge portion to prevent injury to the mantle; substantially as described.
2. A packing box for mantles, comprising a tubular casing of pasteboard or similar non-rigid material and a mantle ring secured within one end portion thereof, said ring being of relatively rigid pre-shaped material forced into the casing to re-form the same and hold it in the desired shape,

said rigid ring having a supporting ledge with a rounded inner edge portion to prevent injury to the mantle; substantially as described.

3. A packing box for mantles, comprising a tubular casing of pasteboard or similar non-rigid material, with a pre-formed mantle supporting ring of relatively rigid material secured within one end portion thereof, said ring having an inwardly projecting ledge with a rounded inner edge for the mantles and provided with an upwardly projecting flange at the end of the box within which the legs of the mantle ring rest: substantially as described.

In testimony whereof, I have hereunto set my hand.

ELMER L. KNOEDLER.
